(57) **CLAIM**

The ornamental structure for an bow rake head, as shown and described.

DESCRIPTION

FIG. 1 is a top plan view of a bow rake head, showing a preferred embodiment of my new design.

FIG. 2 is a rear elevation view of the bow rake head of FIG. 1.

FIG. 3 is a left side elevation view of the bow rake head of FIG. 1, the right side elevation being a mirror image thereof.

FIG. 4 is a bottom plan view of the bow rake head of FIG. 1.

FIG. 5 is a front elevation view of the bow rake head of FIG. 1; and,

FIG. 6 is a perspective view of the bow rake head of FIG. 1, as viewed from the top.

Certain environmental structure, including parts of a rake handle, is shown in broken lines in the drawings for illustrative purposes only and forms no part of the claimed design.
